UNITED STATES PATENT OFFICE.

TALBOT O. BATEMAN, OF FORT WORTH, TEXAS.

ACETYLENE-GAS GENERATOR.

SPECIFICATION forming part of Letters Patent No. 629,485, dated July 25, 1899.

Application filed May 15, 1899. Serial No. 716,790. (No model.)

To all whom it may concern:

Be it known that I, TALBOT O. BATEMAN, a citizen of the United States, residing at Fort Worth, Texas, have invented certain new and 5 useful Improvements in Acetylene-Gas Generators, of which the following is a specification.

This invention relates to apparatus for the production and storing of acetylene gas; and 10 the object is to construct a machine which will be compact in form and simple in construction and perfectly automatic in operation and in which the generating-chamber, the water-supply-tank, the storage-chamber 15 for gas, and a plurality of cups for storing carbid will all be contained in one small vessel cylindrical in form.

Other objects and advantages will be fully explained in the following description and 20 more particularly pointed out in the claims.

Reference is had to the accompanying drawings, which form a part of this application.

Figure 1 is a vertical section of the storage-chambers and the generating-chamber. Fig. 25 2 is a plan view of the machine. Fig. 3 illustrates the arrangement and construction of the carbid-cups, the view being a broken sectional view. Fig. 4 is a detail view of the chute for feeding water to the cups. Fig. 5 30 is a detail view of the casting which holds the generating-chambers in place. Fig. 6 is a front view of the gage for determining the amount of gas in the storage-chamber.

Similar characters of reference are used to 35 indicate the same parts throughout the several views.

The water-compartment A is mounted above the gas-storage chamber B and is provided with an orifice a' and cap b'. A tube C 40 forms a passage from the upper chamber A to the lower chamber B. This tube is provided with a cut-off valve d, which is operated by the rod g, which projects up through the top of chamber A and is provided with a handle f. One or more generating-chambers D are mounted in chamber B. The chamber D is cylindrical in form and has an annular flange h at the top, which flange rests on an interior annular flange k of a casting G. 45 The casting G has a shoulder m on the outside, which forms a joint against the top n of the chamber A. The casting is soldered

air and gas tight to the top n of the chamber A. A gasket-ring p is placed on top of the casting G, and a cap F is screwed on the 55 casting for closing the passage through the casting. Cap F is provided with a handle p'. The generating-chambers D are provided with several small holes j for gas to pass to the storage-chamber B. A small chute H for 60 a water-drip is pivotally attached to the interior of the chamber D. The chute is adapted to cause the water to drop in the center of the carbid-cup and is pivoted so that it will not obstruct the passage of the cups when being 65 taken out of the chamber. The chute H is made and set so that it will yield upward, but not downward. There are several of these cups J, and all are locked together, so that all may be taken out together. Each cup is 70 closed at the bottom and has a chime N at the top with holes M therethrough and a chime P at the bottom with holes M' therethrough. The chime P of one cup rests within the chime N of the next cup below. The holes M and M' 75 are so made that they are in alinement with each other and serve a double purpose. They let the gas escape from the cups, and they are so made that the pipe K will pass through both chimes, and thus lock the cups together. The 80 pipes K serve a double purpose. They serve to convey water to the next cup below and to lock the cups together. These pipes rest in the perforations M M' and may be rigid or flexible. It will be observed that the cups 85 are so arranged that all the carbid in the cup above will be used up, and when the water overflows it will go to the next cup below, and so on until the last cup in the generating-chamber is reached. Water enters through 90 a small opening r just above the water-drip. After the carbid is used up out of one generating-chamber the water will run into another chamber, which has a similar supply of cups of carbid; but the opening r is higher 95 up in the chamber than the opening in the chamber first used. The pipe K leads out of each cup near the top part thereof and enters the cup below through its chime. The water-drip H is attached to the interior of 100 the chamber by attaching, by soldering or otherwise, a piece of E-shaped metal H' and then pivoting the drip H in this piece of metal. Compartment B is provided with a drain-

cock R and a gas-pipe R' for conveying away the gas for consumption. Means are provided for closing the opening through the casting G when a generating-chamber is taken out. The casting has two lugs a projecting downward, to which is hinged a cap E by means of the lug b. Cap E is lined with some elastic packing E'. When one of the chambers D is taken out, the cap E will be pressed 10 against the opening in the casting G by means of a spring E'', which is attached to the top of the compartment B. A gage V is provided for showing the pressure of the gas. A weight V' is attached to the gage by means 15 of a cord V'', which runs over a pulley w and is wound on the usual spring-drum of the gage.

The operation may be described as follows: The carbid is placed in the cups J, and the 20 cups are placed in the generating-chambers D. Water is poured in the compartment B through the openings in the castings G, enough water being put in to come just above the opening r in the generating-chamber after 25 the chamber is put in place. The chamber having the opening r lowest down is the one to be observed in putting in a supply of water. More water can be added after the carbid in the first chamber is used. When 30 the generating-chambers have been put in place, the caps F are screwed down gas-tight on the gasket-rings. Gas will commence to generate as soon as water commences to run on the carbid and escape through the openings j and collect in compartment B and force water up through tube C into compartment A. The pressure of the gas will soon force the water below the opening r, so that too 35 much water will not run on the carbid. Care must be taken to keep the cock d open while gas is being generated. The chamber or compartment A must not be air-tight. The openings for the rods g and V'' will be sufficient for the escape of air when the gas in compartment B forces water up into compartment A. This provision will prevent any 40 danger of explosion. If the pressure of gas becomes great enough to force the water below the mouth of tube C, the gas will escape 45 through the tube C and out of chamber A. The amount of pressure can be determined by the gage V.

Having fully described my invention, what I claim as new, and desire to secure by Letters 50 Patent, is—

1. A gas-generator having a lower compartment, one or more generating-chambers mounted in said compartment, a casting having an annular interior flange for supporting 55 generating-chambers mounted in an opening in the top of said compartment and provided with a gas-tight seal, means for the escape of gas from said generating-chamber, means for distributing water in the central portion of 60 said chamber, and a plurality of cups for holding carbid so arranged in said chamber that the carbid in the upper cup will be decom- 65

posed before the water overflows to the next cup below and the gas will escape and be collected in said compartment for use.

2. A gas-generator having a lower compartment for water and gas, an upper compartment for the retreat of water from the lower compartment, a tube provided with a cut-off valve for the passage of water from one compartment to the other, a casting mounted in an opening in the top of said lower compartment, said casting having an annular interior flange and being provided with a water and gas tight seal, a generating-chamber tubular 75 in form with the bottom closed and the top open and having an annular exterior flange for engaging the flange of said casting, a plurality of carbid-cups placed one above the other in said chamber and having communication one with another from the top down, and means for dripping water in the top cup consisting of a hole in the side of said chamber and a water-drip attached to the interior wall of said chamber below said hole, said 80 chamber having holes for the escape of gas to said lower compartment.

3. In a gas-generator provided with an upper and a lower compartment and a tube for communication of said compartments; a generating-chamber mounted in an opening in the top of said lower compartment and provided with a gas-tight seal on the outside of said compartment and having holes for the escape of gas into said compartment, a plurality of cups mounted in said chamber, each cup having a chime at the top and a chime at the bottom, the chime at the bottom of each cup resting within the chime at the top of the next cup below, a plurality of holes being 95 made through both chimes, a pipe leading from each cup and entering the next cup below through holes in said chimes, and means for dripping water in the cup at the top consisting of a hole in said chamber and a drip 100 attached to the interior wall of said chamber below said hole.

4. In a gas-generator provided with a water-storage compartment, a gas-storage compartment, a tube connecting said compartments, 115 and a generating-chamber; a plurality of cups in said chamber, each cup having a chime at the bottom and a chime at the top, the bottom chime of each cup resting within the top chime of the next cup below and a plurality of holes 120 being made through both chimes, a pipe running out of each cup into the cup below through said holes and locking all the cups together, means for the escape of gas into the lower compartment, and means for dripping 125 water in said cups.

5. In a gas-generator provided with an upper and a lower compartment and a tube allowing passage between said compartments; one or more generating-chambers mounted 130 in said lower compartment, each chamber having a gas-tight seal on the outside of said compartment consisting of a casting mounted in an opening in said compartment, a gasket-

ring on top of said casting and a cap screwed on said casting and gasket-ring, and means for closing the opening in said casting when a chamber has been taken out consisting of a disk hinged to the casting and a spring adapted to press said disk in the opening, said disk being provided with suitable packing.

5 6. In a gas-generator provided with a lower compartment for water and gas, a compartment for the retreat of water from the lower compartment, and a tube allowing passage from one compartment to the other; a generating-chamber mounted in the lower compartment, said chamber being cylindrical in form with closed bottom and open top and having an annular exterior flange at the top, a casting for mounting said chamber having an an-

nular interior flange for engaging the flange of said chamber and a gas-tight seal, a carbid-cup mounted in said chamber, means for dripping water in said cup consisting of a hole in the side of said chamber and a drip pivotally attached to the inside of said chamber below said hole, means for the escape of gas from said chamber into said lower compartment, and a pipe for delivering gas for consumption.

10 In testimony whereof I set my hand, in the presence of two witnesses, this 8th day of May, 1899.

TALBOT O. BATEMAN.
